(57) **CLAIM**

The ornamental design for a multi-plane stabiliser, as shown and described.

DESCRIPTION

FIG. 1 is a top perspective view of a multi-plane stabiliser;
FIG. 2 is a bottom perspective view thereof;
FIG. 3 is a front elevation view thereof;
FIG. 4 is a rear elevation view thereof;
FIG. 5 is a left side elevation view thereof;
FIG. 6 is a right side view thereof;
FIG. 7 is a top plan view thereof; and,
FIG. 8 is a bottom plan view thereof.

The broken lines represent unclaimed features that form no part of the claimed design.
